United States Patent Office

Des. 217,572

Patented May 12, 1970

217,572

TELEVISION MONITOR

Donald N. James and Peter A. Nightingale, Boulder, Colo., assignors to Ball Brothers Research Corporation, Boulder, Colo., a corporation of Colorado

Filed July 1, 1968, Ser. No. 12,578

Term of patent 14 years

Int. Cl. D14—03

U.S. Cl. D56—4

FIG. 1

FIG. 3

FIG. 4

FIG. 2

FIG. 1 is a perspective view of a television monitor embodying our new design;

FIG. 2 is a front elevational view of the monitor shown in FIG. 1;

FIG. 3 is a top plan view of the monitor shown in FIG. 1; and

FIG. 4 is a side elevational view of the monitor shown in FIG. 1.

A portion of applicants' design has been shaded to indicate contrast in appearance.

We claim:

The ornamental design for a television monitor, substantially as shown and described.
